UNITED STATES PATENT OFFICE.

EDWARD R. SNYDER, OF EAST ORANGE, NEW JERSEY, ASSIGNOR TO THE BARRETT COMPANY, A CORPORATION OF NEW JERSEY.

SHINGLE.

1,365,800.

Specification of Letters Patent. Patented Jan. 18, 1921.

Application filed July 10, 1918. Serial No. 244,209.

To all whom it may concern:

Be it known that I, EDWARD R. SNYDER, a citizen of the United States, residing at East Orange, in the county of Essex and State 5 of New Jersey, have invented certain new and useful Improvements in Shingles, of which the following is a specification.

This invention relates to an improvement in roofing materials and is directed more 10 especially to the class of roofings which are formed from a felt base that has been saturated with a waterproofing material and coated with a wear-resisting coating material.

15 An objection to roofings of this class has been that they give to the roof to which they are applied an appearance of cheapness on account of their sameness and uniformity. Different expedients have been adopted in 20 the attempt to make such roofs simulate the appearance of wood shingle or tile roofs, such as variegated colors of the wear-resisting materials, depressions to give shadow effects, and notches to relieve the monotony.

25 By this present invention a shingle of excellent wearing qualities is obtained which may be applied to a roof to give the desired appearance of a roof having a uniform color or a roof having different colors alternating 30 or distributed so as to present a pleasing appearance.

In practising this invention an ordinary saturated felt base shingle is coated with a suitable coating such as asphalt, a layer of 35 wear-resisting material such as crushed stone of one color is applied to one side for about one half of the length of the shingle, and a layer of wear-resisting material of a different color or quality is applied 40 to the opposite side of the shingle throughout substantially the same extent as the first layer, thus obtaining a shingle which is thicker at one end than at the other, having portions of different colors which may be 45 exposed to the weather.

The invention will be more clearly understood from the accompanying drawings in which—

50 Figure 1 represents a side view of a shingle covered on both sides with plastic material and having layers of wear-resisting material applied to a portion of the same;

55 Fig. 2 is a view similar to Fig. 1, with the plastic material extending only as far as the wear-resisting material;

Fig. 3 is a plan view of the shingle; and Fig. 4 is a view indicating the relation of several shingles to each other when applied to a roof.

One the drawings, reference character 1 60 designates a base of saturated felt to which coatings 2 of plastic material are applied. The felt base may be made and saturated by any of the usual methods of manufacture now commonly in use, using as the saturant 65 tar, flux oil, or any other suitable saturant. The coatings of plastic material 2 may be pitch, asphalt or any other suitable coating material known to those skilled in the art, and it may be applied in any of the well 70 known ways.

Instead of the coating being applied to the entire surface of both sides of the shingle, it may be applied to both sides of only a portion of the shingle as indicated in 75 Fig. 2. To the coating material are applied layers 3 and 3' of pebbles, or crushed stone, or crushed slate, or other wear-resisting material, care being taken that the material applied to one side shall be of one color and 80 that applied to the other side of a different color or quality. Any of the old and well known methods of applying the layers of crushed stone, etc., may be employed. The layers should be applied to substantially 85 half of the surface of the shingle on both sides, and the portions covered on the two sides should be substantially co-extensive.

Fig. 4 indicates how the shingles may be applied in successive courses with the coating 3 of one color exposed in one course and the coating 3' of another color exposed in the next course and so on, alternating over the entire roof. It will be obvious that the shingles may be laid with all of the exposed 95 surfaces of the same color, or may be laid with the colors alternating in the same course, or any other arrangement of the relations of the colors may be adopted within the discretion of the user.

100 It will thus be obvious that with this invention it is possible to obtain a variety of effects simply by a choice of the way in which the shingles are turned as they are laid, even though each shingle is like the 105 others. This obviates the necessity for the purchaser to procure a supply of two or more different sorts of shingles in order to procure a variegated color scheme for his roof.

110

It will also be seen that the thickness of the felt base 1 together with two layers 2 of plastic material and the two layers 3 and 3' of wear-resisting material will produce 5 a shingle of considerable thickness at one end, thus relieving the "flat" appearance when applied to a roof or the side of a wall. The shingles will be laid with the wear-resisting portions slightly overlapping, thus 10 leaving only the colored portions exposed.

It is preferable to use materials which differ naturally in color, such, for example, as slate and limestone, as the wear-resisting materials for the two respective sides of the 15 shingles, although materials which have been artificially colored may be used with satisfactory results provided they retain their colors permanently.

While this invention has been described 20 as applied to a single shingle, it is to be understood that it may be also applied with certain advantages to strips of roofing material which are slotted on one edge for some distance to resemble a series of shingles. 25 The expression "shingle" as used in the claims is intended to include a strip of roofing material, which may consist of one shingle or a number of shingles integrally connected to each other.

30 What I claim is:

1. A shingle of the class described having one end covered on one side with a wear-resisting material, and covered on the other side of the same end with a different sort of 35 wear-resisting material.

2. A shingle of the class described having substantially half of one side covered with a wear-resisting material and having the corresponding portion of the other side 40 covered with a different sort of wear-resisting material.

3. A shingle of the class described having one end free from wear-resisting material and the two sides of the other end covered 45 with wear-resisting material of different colors.

4. A shingle of the class described, the thickness of one end of which is determined by the thickness of the saturated felt base 50 used in its manufacture; the thickness of

the other end being determined by the thickness of the felt base, two layers of plastic coating material and two layers of wear-resisting material, said layers of wear-resisting materials being disposed on opposite 55 sides of the felt base.

5. A shingle of the class described one end of which comprises a felt base; the other end of which comprises a felt base, a layer of plastic material on each side of the 60 felt base, and layers of wear-resisting material of different colors applied to the plastic layers.

6. A shingle of the class described, having both sides of one end covered with layers of wear-resisting material. 65

7. A shingle of the class described, having the two respective sides of one end covered with layers of wear-resisting material 70 of different colors.

8. A shingle of the class described, having one end covered on one side with a wear-resisting material of one color and covered on the other side of the same end with wear-resisting material of a different color. 75

9. A shingle of the class described, having substantially half of one side covered with wear-resisting material of one color and having the corresponding portion of the other side covered with wear-resisting 80 material of a different color.

10. A shingle of the class described, having one end covered on one side with a wear-resisting material, and covered on a portion of the other side with a different 85 sort of wear-resisting material.

11. A shingle of the class described, having one end covered on one side with a mineral wear-resisting material, and covered on the other side of the same end with 90 a wear-resisting material of a different color.

12. A shingle of the class described, having crushed stone applied to one side and having wear-resisting material of a different color applied to a portion of the other side. 95

13. A shingle of the class described, having wear-resisting facings of different colors on the two sides thereof.

In testimony whereof I affix my signature.
EDWARD R. SNYDER.
